MOTION PICTURE APPARATUS

Louis Gross, Lausanne, Switzerland

Application March 24, 1932, Serial No. 600,996
In Switzerland April 2, 1931

5 Claims. (CL 88—16.2)

This invention relates to motion picture apparatus and more particularly to means for producing a synchronized accompaniment to the projection of a film in accordance with the variations 5 of intensity and movement of the light on the screen.

Cinematography may be considered an art the means of expression thereof being the movement which is rendered perceptible by images which may vary in shape, position and luminosity. 10 The projecting devices which are used in this art are noisy and for this reason it has become the use to accompany the projection of a film by music to cover the noise of the projecting apparatus. Music however has its own rhythm and 15 signification and has the effect to introduce a disturbance into the impressions of the spectator. It is possible to conceive an art of movement of which the means of expression would be reinforced by a production of perceivable phenomena 20 which are exactly synchronized with the fluctuations of the image projected on the screen.

The present invention has as its object the provision of an accompaniment to the projection 25 of moving pictures as set forth above by the production of acoustical, visual or other phenomena. These phenomena may be of a physically definable character such as intensity of sound, its pitch and its timbre or stamp, or as color or 30 intensity of light. Such characters may vary for each particular film or given part of a film according to arbitrary but fixed laws by means of which laws these characters are made dependent on the position of illuminated points and of the 35 instantaneous degree of illumination of such points.

My invention will be clearly described herein- 40 after, reference being had to the accompanying drawings in which,

Figure 1 a general diagrammatic view of an apparatus for carrying out the invention;

Figure 2 shows a series of relays connected to mechanical operating devices;

Figure 3 shows a part of the apparatus comprising a relay tube with three electrodes;

Figures 4, 5 and 6 show each a portion of the apparatus in which photo-electric cells are disposed in various manners;

Figure 7 is a diagram showing partially the 50 connections of a series of photo-electric cells with sound producing apparatus;

Figure 8 shows a complementary device which may be added to that shown in Figure 1 and destined for phono-photographic recording.

Figures 9 and 10 show each a diagrammatic

representation of a film carrying a sound record obtained according to the present invention.

In Figure 1, the projecting apparatus 1 is provided with two objectives 2 and 3. The objective 2 projects the pictures of a film F as usual on the screen 4 which is for example situated in a moving picture show room, while the objective 3 of relative great angular aperture projects the pictures on a screen 5 situated in the cabin of the operator. This screen 5 is constituted by juxtaposition of a great number of photo-electric cells. 10 Each of these cells is electrically connected to one or several succeeding relays. The last one of such succeeding relays can be arranged to have a mechanical action for producing sound either directly by operating sound apparatus or indirectly by acting on the operating members of a known musical instrument. For example there may be provided as many final relays as there are keys or utilized notes of one or several musical instruments such as pianos, organs or others.

In Figure 1 it is seen that the various photo-electric cells 7 may be connected to the relays by means of a plug-switchboard 6 permitting to vary the connections between the cells and the relays, that is to say to connect any particular cell with any particular relay or group of relays and thus with any particular sound producing means connected to the terminals 8 of the switch board 6.

As shown in Figure 2, this switchboard can be placed in the line leading away from the last relay. In this figure there have been represented one of the cells 7, a source of electricity 9, a first relay 10 acting on the armature 10' to close the circuit of an electromagnet 11 having a movable core 13 and connected to a source of electricity 12. The core 13 is subjected to the action of a retracting spring 14 and can for example control the admission of air into an organ pipe 16 by operating the valve 15. Figure 2 shows also that the last relay can act directly by means of an electromagnet 11 on one of the keys 18 of a keyboard of a piano, organ or like instrument.

The Figure 3 shows a part of the installation in which a cell 7 is connected to the sound producing apparatus by the intermediary of a relay constituted by an amplifying tube 19 having three electrodes and to the grid 20 of which the cell is connected. The electromagnet 21 can act upon any musical instrument and the electromagnet 22 with its armature 23 can operate sound devices such as a bell 24.

The case where the relay will be constituted by the electron tube 19 is here described as par-

5
ticularly applicable to the embodiment of an installation comprising a recording device as represented in Figure 8 and the same is the case for the embodiments according to Figs. 4 to 7, but the devices shown in these figures are also applicable to the general form of an installation comprising no recording means.

10 Figures 4, 5 and 6 show three screens 5 on the surfaces of which are disposed the photo-electric cells. These cells 7 may be arranged in straight lines 26, or in concentric circles 25 which may be equidistant as shown in Figure 4 or may be nearer to each other towards the center as are the circles 27 in Fig. 5. The cells 7 are disposed on these circles in such a way that their number in proportion to the surface is increased towards the center of the screen, as the greatest attraction for the spectator will usually be in the center of the picture.

15 20 In Figure 7 a screen of photo-electric cells has been represented in which the cells are disposed according to concentric rectangles. It has been shown how the cells of one group can be connected each to an electron tube relay 19, 19', 19'' and to oscillating circuits 28, 28', 28'', and together to an amplifier 30 connected to a telephonic receiver or loud speaker 31.

25 The loud speaker can be connected to several 30 separate amplifiers 30 of which the amplifying capacity is more powerful the nearer the corresponding group of photo-electric cells is disposed towards the center of the screen, so that a prevailing effect is given to the movement of the picture adjacent the center of the screen.

30 35 In Figure 8, a microphone 31 is made to vibrate by the action of the noise or sound accompaniment of a film as F in Fig. 1 which is projected on a screen 5 constituted by photo-electric cells. This device shown in Fig. 8 is destined to produce 40 a permanent record of the sound accompaniment of a film. The microphone 31 is connected by one or several electron tubes 32 to a galvanometer 33 having a mirror 34 of which the deflection is proportional to the intensity of the current. 45 A source of light 35 illuminates the mirror which sends a light beam to a film f moving perpendicularly to the plane of the figure. When the film f is developed it carries a sound record which may be reproduced in the ordinary manner. This 50 film f may be then associated with the picture film F and copies can be made of both films separately or while they are united. It is therefore possible that all existing installations for the 55 projecting of sound films can reproduce the accompaniment of the film F recorded on the film f.

55 The mirror 34 of the galvanometer 33 may be replaced by a specular diaphragm which is made to vibrate directly by the sound or noise which 60 is to be recorded.

60 It follows from the foregoing that the invention may be used for two different purposes. According to the first use of the invention, a sound accompaniment of a film can be obtained 65 without adding anything to a usual silent film. But in this case it is necessary that each theatre in which a film is shown and when such an accompaniment is desired, be equipped with an installation comprising the elements shown in 70 Figures 1 and 2 or, 1, 4 to 7. The screen 5 carrying the photo-electric cells may be placed also immediately behind the ordinary projection screen 4.

75 In order to prepare a film for projection with an accompaniment according to the invention,

the film will be projected on the screens 4 and 5 and the picture as well as the produced sound will be watched. The connections of the switch board 6 will then be made, and changed when necessary, so that the sound produced by the instrument to which the cells are connected is not the result of a mixture of any sounds capable of being emitted, but gives a compound of harmonic and agreeable tones or sounds.

These may be for example succeeding perfect 10 major or minor chords of which certain tones prevail over others when a given place on the screen receives more light and other places receive less light. When a relay in the form of an 15 electron tube is used, the sound produced by each cell of the screen can have an intensity which is proportional to the luminous flux acting on the cell. When once the desired adjustment of the connections on the switchboard 6 has been achieved, the film can be projected any number 20 of times and always the same sound effects will be obtained. In the case of an installation according to Fig. 1, such an adjustment must be made however for each different projecting installation. It is therefore an advantage to use 25 the sound recording device according to Fig. 8 so that the setting of the switchboard has to be made once only for one film. The invention is not limited to the production of an acoustical 30 accompaniment for the projecting of films; the 35 action of the screen of photo-electric cells could be used also to produce light effects, for example to diffuse colored lights in the film show room of which the color could vary with the fluctuations of the pictures.

35 Figures 9 and 10 show each a sound record obtained with a device according to Fig. 8 for two particular cases of picture films. In Figure 9 the picture film 36 is supposed to be composed of successive images of which the mean transparency is invariable and which represent moving objects diagrammatically represented by black 40 lines 41. In this case the sound record 37 obtained according to the described method from the picture film 36 and which will be placed 45 on the space 38 reserved for this purpose on the picture film, is provided with portions a', b', c', d', of a length corresponding to the length of successive images a, b, c, d, each length of the 50 sound record varying from its succeeding length in accordance with the variations of the movable objects on the corresponding images. The movement of the represented black lines with respect to the photo-electric cells receiving light across the film produces a change in the sound emitted 55 by the sound producing instruments controlled by the cells. These changes appear in the sound record 37 as variations of the tone and of the 60 frequency only when it is supposed that all sound producing instruments are so adjusted that they produce sounds of equal intensity (amplitude of the oscillations) and when it is further supposed that the movements of the black lines are such that the photo-electric cells are either fully 65 illuminated or entirely dark. The sound record 37 represents therefore oscillations of constant amplitude. It will be understood that the represented case is simplified to the extreme and that in reality the sound record will contain variations of tone and variations of intensity and frequency.

70 Figure 10 represents another extreme case in which the successive images of the film differ only in their mean transparency. In this case the sound record 48 obtained with the described 75

method from the picture film 38 comprises lengths *a'*, *b'*, *c'*, *d'* of which the mean transparency varies according to the mean transparency of the corresponding images *a*, *b*, *c*, *d*. With the diagrammatic representation of the sound record in Fig. 10 it will in reality be the amplitude of the oscillations of the sinuous line representing the record which will be proportionate to the mean transparency. The sound record has been shown secured to the picture film with a certain displacement between the images of the film and the corresponding lengths of sound record to take care of the difference in the speed of propagation of sound waves and light waves and also of the distance between the two objectives 2 and 3 of the projection apparatus shown in Fig. 1.

I claim:

1. Motion picture apparatus comprising a picture screen, a sound screen including a plurality of photo-electric cells disposed over the surface of the screen, electric circuits including said photo-electric cells, projecting means for simultaneously projecting the pictures of a picture film on said picture screen and on said sound screen, sound producing instruments, and electrically operated means included in said circuits for actuating the sound producing instruments upon said photo-electric cells closing said circuits.
2. Motion picture apparatus comprising a picture screen, a sound screen including a plurality of photo-electric cells disposed over the area of the screen, a picture film projection machine including two objectives, means for moving a picture film in front of both objectives for simultaneously projecting the pictures of the film on the picture screen and on the sound screen, sound producing instruments, electrically operated means for actuating said sound producing instruments, and electric circuits including said photo-electric cells and said electrically operated means whereby said sound producing instruments are operated upon the photo-electric cells closing said circuits.
3. The method of producing a combined sound and picture film, which comprises projecting a beam of light across a moving picture film on a screen formed of a plurality of photo-electric

cells, interposing each photo-electric cell in an electric circuit whereby the circuit will be controlled by the light falling across the picture film on said cell, including electrically operated actuating means for sound producing instruments in said circuits whereby variations in translucency at a certain point of the moving picture film will produce corresponding variations in the electric circuit controlled by the light traversing said point of the picture film, photographically recording the sound produced by said sound producing instruments upon projection of the film on said screen, and then associating the photographic sound record with said picture film.

4. The method of producing a combined sound and picture film, which comprises projecting a beam of light across a moving picture film on a screen formed of a plurality of groups of electrically interconnected photo-electric cells, including each group of interconnected cells in an electric circuit whereby said circuit will be influenced by the light falling across the picture film on the photo-electric cells included in said circuit, including electrically operated actuating means for sound producing instruments in each circuit whereby variations in translucency of a certain point of the picture film will produce corresponding variations in the electric circuit influenced by the light traversing said point of the picture film, photographically recording the sound produced by said sound producing instruments upon projection of the picture film on said screen and then associating the photographic sound record with the picture film.

5. A combined sound and motion picture film comprising a plurality of successive images representing picture scenes, and a photographic sound record, said sound record comprising portions of a length equal to the length of each individual image of the picture film, the characteristics of the successive portions of the sound record varying in accordance with the variations in translucency and with the variations in the repetition of light and dark zones of the corresponding successive images of the picture film.

LOUIS GROSS.
